INJURY PAD

Roland F. Logan, Los Angeles, Calif.

Application March 23, 1948, Serial No. 16,591

3 Claims. (Cl. 2-24)

1

This invention relates to injury pads and more particularly to a pad which is adapted to interchangeable use on various parts of a human body.

It is an object of the invention to provide a pad of soft material which may be affixed to a vulnerable body area for the prevention of injuries or for the protection of injuries that may have been received. The pad may find an extensive use in physical contact sports, such as football and hockey.

Specifically, the pad provides a body covering unit consisting of a semi-cylindrical limb embracing section and a quadrисpherical end section which provides a cup-like protector for a joint or the like, particularly susceptible to injury. In its most specific form, the pad is molded of soft rubber in the shape specified, and is adapted to be removably attached to the human anatomy by means of ordinary surgical tape.

Further advantages and objects of the invention will appear and the full nature of the pad will be understood as the description herein is read in connection with the drawings forming a part of the application, in which drawings:

Fig. 1 is a perspective view of the injury pad applied to a human knee.

Fig. 2 is a perspective view of the pad showing the normal shape thereof.

Fig. 3 is a longitudinal cross sectional view on the line 3-3 of Fig. 4.

Fig. 4 is a transverse cross sectional view on the line 4-4 of Fig. 3.

Fig. 5 is a perspective view of the pad applied to a shoulder joint.

Fig. 6 is a perspective view of the pad applied to an elbow.

Fig. 7 is a perspective view of the pad applied to a human hip.

The pad 10 is composed of a body of relatively thick, soft, shock-absorbing material, and it consists of a flexible, semi-cylindrical body section 12 and a flexible, quadrисpherical end section 14. The semi-cylindrical section 12 is adapted to partially encircle and embrace a limb, as shown in Figs. 1, 5, 6 and 7, while the quadrисpherical section 14 forms a protective cup over the injured area or over an area that is particularly vulnerable to injury.

In the specific embodiment herein illustrated, the pad is molded of soft, flexible, and to some extent elastic, rubber. The softness, flexibility and limited elasticity of the material requires that the pad be reinforced, and such reinforce-

2

ment is herein provided by an inelastic, tough fabric facing 16 which is permanently attached, as by cementing or vulcanizing, to the outer face of the semi-cylindrical section 12. The attached facing 16 extends over the major portion of the semi-cylindrical section 12.

The function of the inelastic, tough fabric facing 16 is two-fold. When the pad is molded of relatively soft, cellular rubber, the face of such rubber material is usually susceptible to easy rupture and tearing. Inasmuch as the pad is designed for application to body areas by means of an adhesive strip, the repeated application and removal of such strips would rapidly destroy the body of the pad by tearing from the adhesive strip receiving face thereof, pieces of the rubber material. Such tearing and gradual destruction is avoided by permanently affixing to the face of the adhesive strip receiving portion, the tough fabric covering 16. As a consequence of the durable nature of the facing 16, adhesive strip may be applied and removed repeatedly without in any way affecting the adhesive strip receiving surface of the pad.

25 Perhaps a more important function of the inelastic facing 16 is its cooperation with the quadrисpherical section to impart to the pad a certain degree of rigidity which is necessary if the quadrисpherical section 14 is to be properly positioned over the body areas to be protected. Thus, while the quadrисpherical section 14 is perfectly flexible and to some extent elastic, the semi-cylindrical section 12 is rendered completely inelastic and less flexible by the fabric facing 16. This difference in the character of the sections 12 and 14 aids materially in shaping the pad to various areas that are to be protected. Thus, in Fig. 1, the pad in its more or less natural shape is well adapted to protect the wearer's knee. The pad in a slightly altered shape is equally well adapted for application to a shoulder, as seen in Fig. 5. The utility of the inelastic fabric facing 16 is, however, most marked when the pad is substantially deformed for application to areas such as 30 an elbow or hip, as particularly shown in Figs. 6 and 7. The quadrисpherical section operates to lend stability to the cup-shaped end. Because of the rounded inner marginal edges of the quadrисpherical section, all danger of liping-out 35 is avoided when the pad is conformed to any given body area.

One of the appealing advantages of the pad as herein described, lies in the fact that a pad of single shape and unembellished by fastening 40 straps or the like, is capable of substantially uni-

versal application to the body joints by the simple expedient of deforming the pad to the required contour, and removably attaching the pad by means of adhesive tape 18 as may be required.

Having described the invention in a specific 5 form, what I claim is the following:

1. A pre-formed injury pad consisting of a flexible semi-cylindrical body section, a flexible quadrispherical end section and an inelastic fabric facing attached only to the entire outer 10 surface of said semi-cylindrical body section.

2. A pre-formed injury pad of soft rubber consisting of a flexible semi-cylindrical body section, a flexible quadrispherical end section, and an inelastic fabric facing attached only to the entire 15 outer surface of said semi-cylindrical body section.

3. A pre-formed injury pad of soft rubber consisting of a flexible semi-cylindrical body section, a flexible quadrispherical end section having 20 rounded inner marginal edges and an inelastic

fabric facing permanently attached only to the entire outer surface of said semi-cylindrical body section.

ROLAND F. LOGAN.
